(57) **CLAIM**

The ornamental design for a display screen with graphical user interface or portion thereof, as shown and described.

DESCRIPTION

The present application is related to U.S. patent application Ser. No. 29/488,692, filed concurrently herewith, and to U.S. patent application Ser. No. 29/488,695, filed concurrently herewith, the entire disclosures of which are incorporated herein by reference.

FIG. 1 is a front view of a display screen with graphical user interface or portion thereof, according to a first embodiment; FIG. 2 is a front view of a display screen with graphical user interface or portion thereof, according to a second embodiment;

FIG. 3 is a front view of a display screen with graphical user interface or portion thereof, according to a third embodiment;

FIG. 4 is a front view of a display screen with graphical user interface or portion thereof, according to a fourth embodiment;

FIG. 5 is a front view of a display screen with graphical user interface or portion thereof, according to a fifth embodiment; and,

FIG. 6 is a front view of a display screen with graphical user interface or portion thereof, according to a sixth embodiment.

The outermost broken line rectangle showing a display screen in FIGS. 1 and 4, and the broken line showings of text and other features in FIGS. 1-6 are included for the purpose of illustrating portions of the article and form no part of the claimed design.

The perimeters of the portion of the underlying portion of a display screen and the graphical user interface in FIGS. 2, 3, 5 and 6 are understood to be flush.
